UNITED STATES PATENT OFFICE.

JOHN BRUCE, OF PITTSBURGH, PENNSYLVANIA.

MEANS FOR CLEANING SEWERS.

1,087,721.

Specification of Letters Patent. Patented Feb. 17, 1914.

Application filed July 24, 1912. Serial No. 711,368.

To all whom it may concern:

Be it known that I, JOHN BRUCE, a citizen of the United States, and a resident of Pittsburgh, in the county of Allegheny and 5 State of Pennsylvania, have invented an Improved Means for Cleaning Sewers, of which the following is a specification.

Branch sewers, extending between houses and main sewers, often become obstructed 10 and choked by various materials, the removal of which involves time and labor to such a degree as to render the operation comparatively expensive besides putting the sewers out of use for a considerable period. 15 I have conceived an improved device for relieving the choke and cleaning out such sewers, the operation being quickly effected and at small expense.

In carrying out the invention, a small 20 opening is cut in the sewer and my improved cleaning device is introduced through such opening and then rotated by means of a hand brace or other equivalent. The cleaning device is constructed of steel wire, preferably in the form of a loop, and the free 25 ends of the strands of wire are secured in a suitable clamp which is, in turn, attached to a hand-brace.

The details of construction and operation 30 are as hereinafter described and illustrated in the accompanying drawing, in which—

Figure 1 is a sectional view of a branch sewer and main sewer with my improved cleaner introduced as in actual use. Fig. 2 35 is an enlarged cross section on the line 2—2 of Fig. 1. Fig. 3 is a perspective view of the main parts of the clamp in which the end of the cleaner is secured and by which it is attached to the hand-brace.

In Fig. 1, the cleaner proper is indicated 40 by 1, the same being formed of a length of steel wire doubled upon itself at the middle of its length, thus forming an extended narrow loop having its free or outer end rounded. The ends of the wire strands are held 45 in a clamp—see Figs. 2 and 3—formed of two duplicate jaws 2 whose enlarged flattened ends are provided with grooves 3 to receive the wires. A screw-bolt 4 and wing 50 nut 5—see Fig. 2—serve to clamp the jaws 2 upon the wires, as shown in Figs. 1 and 2. The shanks of the jaws 2 are reduced and tapered, and adapted, when placed together, 55 as in Fig. 1, to be inserted and secured in the socket of a hand-brace 6.

In order to obtain access to a branch

sewer *x*, which has become obstructed or choked, the earth over the sewer is removed, as indicated at *y* in Fig. 1, and a slot or opening 7 is formed in the sewer *x*. This 60 opening is preferably formed close to the first trap where the downpipe from the roof is connected. The meeting ends of the wire cleaner 1 are then inserted through the opening 7 and gradually fed into the sewer *x*, 65 this being done by an operator standing on the ground above. Two operators are employed, one for introducing the cleaner proper 1 and the other for rotating the hand-brace, since it is practically impossible to conveniently introduce the cleaner 70 except when rotated during the operation. In other words, if the cleaner be rotated and introduced at the same time, the latter operation is easily effected. The cleaner may 75 be introduced far enough to extend into the main sewer *z*, as illustrated in Fig. 1. As soon as the cleaner reaches the choke or obstruction, it begins to break up and penetrate the same, and very soon, operating on 80 the principle of an auger, it passes through the obstruction and quickly removes it altogether, so that it may be washed down into the main sewer. In the same manner the cleaner operates in the main sewer itself to 85 break up and remove any obstruction located adjacent to the mouth of the branch sewer *x*. During this operation, it will be understood that the cleaner may be rotated effectively even though it describes a considerable 90 angle. In fact, if it should be crooked or slightly bent when introduced into the sewer, this may be an advantage rather than a detriment to its operation, for, upon being revolved, its strands expanding, as illus- 95 trated in Fig. 1, into contact with the wall of the sewer, will sweep the surface thereof and thus clean it more effectively.

It will be seen that by means of my device no digging is required save to form an 100 opening in the earth sufficient to permit access to the branch sewer for the purpose of forming the opening required for introduction of the cleaner. After the cleaning operation has been effected and the cleaner 105 withdrawn, the closure of the opening 7 by cement or other suitable means is easily and quickly effected. The whole operation of opening the ground to the sewer and introducing the cleaner and removing the ob- 110 struction may be so quickly effected that the sewer is out of use but a very short time.

In practical experience, I have found that steel wire of 8, 9, or 10 gage may be employed to advantage.

What I claim is:—

- 5 1. The improved device for removing obstructions of sewers, consisting of a body portion formed of two lengths of spring wire arranged side by side, a holding clamp formed of parts adapted to receive and hold 10 the inner ends of the wires, and a device adapted for application to the clamp and for rotating the clamp and wire, as described.
- 15 2. The improved device for removing obstructions of sewers, consisting of an integral loop of spring wire formed of a length of wire doubled upon itself at the middle of its length, the outer end of the loop being rounded, and a holding clamp 20 adapted to be applied and secured to the ends of the wire composing the loop and

having the form of a crank brace, for rotating the loop manually, as described.

3. The improved device for removing obstructions of sewers, consisting of a single 25 spring wire doubled upon itself at the middle of its length, thus forming an integral loop, the strands of which extend alongside each other, a crank brace provided with a clamp consisting of duplicate jaws adapted to receive and hold the ends of the said loop, and a screw bolt applied to such jaws and provided with a wing nut for clamping them on the wires, the shanks of the jaws being reduced and tapered and thus adapted for 30 application to a hand brace for rotating the device, as described.

JOHN BRUCE.
